tion of Massachusetts

Application April 28, 1939, Serial No. 270,594

7 Claims. (Cl. 121—45)

The invention relates to grinding machines, and more particularly to a manually actuated and controlled hydraulic table traverse mechanism therefor.

5 One object of the invention is to provide a simple and thoroughly practical grinding machine table traversing mechanism. Another object of the invention is to provide a manually controlled table traverse mechanism by which 10 the table may be traversed easily without undue exertion on the part of the operator. Another object of the invention is to provide a manually controlled hydraulically operated table reversing mechanism. Another object of the invention is to provide a manually controlled hydraulically actuated table traversing mechanism in which the speed of movement of the control member, such as the rotation of a hand wheel, serves to 15 control the rate of traversing movement of the table. Another object of the invention is to provide a fluid pressure operated manually permitted table traverse mechanism. A further object of the invention is to provide a low pressure hydraulic traversing mechanism for the table combined 20 with a manually operable mechanism including a worm and worm gear mechanism to govern and control said hydraulic movement. Other objects will be in part obvious or in part pointed out hereinafter.

25 The invention accordingly consists in the features of construction, combinations of elements, and arrangements of parts, as will be exemplified in the structure to be hereinafter described, and the scope of the application of which will be indicated in the following claims.

In the accompanying drawings, in which is shown one of various possible embodiments of the mechanical features of the invention,

Fig. 1 is a front elevation of a cylindrical grinding machine embodying this invention;

Fig. 2 is a diagrammatic illustration of the hydraulic system combined with an electrical wiring diagram;

Fig. 3 is a fragmentary front elevation, on an enlarged scale, of the manually operable traverse mechanism, having the front cover removed;

Fig. 4 is a cross sectional view taken approximately on the line 4—4 of Fig. 3;

Fig. 5 is a fragmentary sectional view taken approximately on the line 5—5 of Fig. 3;

Fig. 6 is a fragmentary sectional view, on an enlarged scale, taken approximately on the line 6—6 of Fig. 5; and

Fig. 7 is a cross sectional view taken approximately on the line 7—7 of Fig. 6.

A cylindrical grinding machine has been illustrated in the drawings comprising a base 10 having a transversely movable wheel slide 11 which is movable transversely on the usual V-way and flat way (not shown). A rotatable grinding wheel 12 is mounted on a wheel spindle 13 which is supported for rotation in bearings (not shown) on the wheel slide 11. The grinding wheel 12 may be rotated by any suitable source of power, either by means of a driving belt from an overhead countershaft, or it may be driven by an electric motor 14 mounted on the upper surface of the wheel slide 11. The motor 14 is provided with an armature shaft 15 which supports a driving pulley 16. The pulley 16 is connected by a 10 driving belt 17 with a pulley 18 mounted on the right-hand end of the wheel spindle 13 (Fig. 1).

The base 10 also serves as a support for a longitudinally traversable or reciprocable table 20 which slides longitudinally on a V-way 20a and 20 a flat way 20b on the base 10. The table 11 serves as a support for a rotatable work supporting mechanism rotatably to support a work piece 21. The work piece 21 is supported at its left-hand end (Fig. 1) by means of a headstock center 22 which is carried by a headstock 23. The other end of the work piece 21 is supported by a footstock center 24 which is carried by a footstock 25 supported on the table 20.

The wheel slide 21 is arranged for a transverse 30 feeding movement to cause the grinding wheel 12 to approach or recede from the work piece 21 so as to grind the same to a predetermined size. A well known type of wheel feeding mechanism is provided comprising a half nut and rotatable cross feed screw (not shown) which is actuated by a manually operable feed wheel 28 rotatably supported on the front of the machine base. The feed wheel 28 is provided with a micrometer adjusting mechanism 29, and is arranged to be rotated either manually or automatically by means of a reciprocable picker or ratchet pawl 30. The details of the grinding wheel feeding mechanism have not been illustrated in the present case, since they are not considered to be a part of the present invention.

The wheel feeding mechanism utilized is substantially the same as that shown in the prior United States Patent to C. H. Norton No. 762,838 dated June 14, 1904. For details of disclosure 50 as to the wheel feeding mechanism not found herein, reference may be had to the above-mentioned patent.

A power operated traversing or reciprocating mechanism is provided to cause a relative lon- 55

litudinal traversing movement between the rotatable work piece 21 and the rotatable grinding wheel 12 so as to grind the work piece throughout its length to the required cylindrical form.

5 A fluid pressure operated reciprocating mechanism is provided comprising a fluid pressure cylinder 35 which is fixedly mounted relative to the base 10 of the machine. A piston 36 is slidably mounted within the cylinder 35 and is provided with a double end piston rod 37 which extends through the opposite ends of the cylinder 35 and is fastened to depending brackets 38 and 39 which depend from the opposite ends of the longitudinally movable work supporting table 20. The brackets 38 and 39 are either formed integral with the table or rigidly fixed thereto. A control or reversing valve 40 (Fig. 2) is provided to control the direction of movement of the piston 36 and the table 20. A valve 40 is a piston type valve comprising a valve stem 41 having formed integrally therewith a plurality of valve pistons 42, 43, 44, 45 and 46. A fluid pressure reservoir 50 is preferably located within the base 10 of the machine. Fluid is pumped from the reservoir 50, through a pipe 51, by means of a motor driven fluid pressure pump 52, and is forced through a pipe 53 to the table traversing mechanism in a manner to be hereinafter described.

30 A manually operable start and stop valve 55 is interposed between the pump 52 and the control valve 40 and serves to control not only the admission of fluid under pressure to the valve 40 and table cylinder 35 but also to control the exhaust of fluid therefrom. The valve 55 comprises a valve stem 56 having formed integrally therewith a pair of valve pistons 57 and 58. Fluid under pressure passing through the pipe 53 passes through a pipe 59 and a pipe 60 into a valve chamber 61 located between the valve pistons 57 and 58 and passes out through a pipe 62 which connects with short pipes 63 and 64 to convey fluid under pressure to the table control valve 40. Fluid exhausting from the table cylinder 35 through the valve 40 passes out through a pipe 65 and through a V-port 66 into a chamber 67 formed between the valve piston 58 and the end of the valve casing 55 and exhausts through a pipe 68 into the reservoir 50.

50 The right-hand end face of the valve piston 58 (Fig. 2) is angled off so as to provide a fine control of the exhausting of fluid from the system. By rotating the valve stem 66, the angled-off end face of the valve 58 closes more or less of the V-port 66, as desired, and thereby controls the normal traversing speed of the table when it is being reciprocated by power. A serrated portion 70 formed integral with the valve stem 56 is engaged by a spring-pressed detent 71 which serves to hold the valve stem 56 in adjusted rotary position but at the same time permits an end-wise movement thereof when desired to cut off fluid pressure and exhaust of fluid from the table cylinder without upsetting the adjustment of the valve for the normal table speed.

65 A manually operable control lever 75 is pivotally mounted on a stud 76 which is carried by a bracket 77 fixed relative to the base 10. The lever 75 is pivotally connected to the valve stem 56 in such a manner that the valve stem 56 may 70 be moved in an axial direction when desired. A manually operable knob 78 is mounted on the end of the valve stem 56 to facilitate rotation of the valve to adjust the normal traversing speed of the power traversing movement of the table 20. The details of the control lever and

its connection with the valve stem 56 have not been illustrated in the present case, since this valve control mechanism is identical with that shown in the prior United States Patent to Wallace H. Wood No. 2,071,677 dated February 5 23, 1937, to which reference may be had for details of disclosure not contained herein.

In the position of the lever 75 and the valve pistons 57 and 58, fluid under pressure is admitted to and exhausted from the control valve 10 40 and table cylinder 35. If it is desired to stop the automatic power reciprocation of the table, the lever 75 is moved in a clockwise direction (Fig. 2) to shift the valve stem 56 toward the right, thus moving the valve pistons 57 and 15 58 toward the right so that the piston 57 covers the ports connecting the valve chamber 61 with the pipes 60 and 62 to cut off fluid under pressure from the control valve 40, and at the same time 20 the valve piston 58 covers the V-port 66, thus cutting off exhaust of fluid from the table reciprocating mechanism.

25 During the automatic power reciprocation of the table, the reciprocatory stroke thereof is automatically controlled by means of a pivotally mounted reversing lever 80 which is pivotally supported by a stud 81 on the front of the machine base 10. A pair of adjustable table dogs 82 and 83 are adjustably supported in a T-slot 84 formed in the front edge of the table 20. The 30 dogs 82 and 83 are arranged in the path of the reversing lever 80 so as to shift the lever 80 and thereby shift the control valve 40 into its reverse position to change the direction of flow of fluid under pressure to the cylinder in a manner substantially the same as that disclosed in the prior United States Patent to Wood No. 2,071,677 above referred to.

35 To attain the main object of the invention, a manually controlled hydraulic table traverse 40 mechanism is provided whereby the table 20 may be manually traversed longitudinally without undue effort on the part of the operator. In the preferred construction, a fluid pressure system is provided which provides sufficient pressure to 45 move the table longitudinally at a desired rate of speed, and a manually operable control mechanism is provided which is arranged to prevent such fluid pressure movement unless the manual mechanism is actuated to produce the traversing 50 movement of the table. This mechanism is, therefore, a hydraulically operated manually permitted motion whereby the speed of movement of the manually operable mechanically controlled mechanism determines the speed of traversing 55 movement of the work supporting table.

60 As illustrated in the drawings, a manually operable table traverse control apron 95 is mounted on the front of the machine base 10. The apron 95 rotatably supports a shaft 96 in a pair of spaced antifriction bearings 97 and 98. The right-hand end of the shaft 96 (Fig. 4) is provided with a gear 99 which meshes with a rack bar 100 depending from the under side of the table 20. A manually operable mechanism is provided to rotate 65 the shaft 96 and thereby to control the speed of movement of the table 20 when manually traversed. A manually operable hand wheel 102 is rotatably supported on a shaft 103 which is journaled in the apron 95. A bevel gear 104 which is rotatably supported on the shaft 103 meshes with a bevel gear 105 which is supported on a rotatable shaft 106. The shaft 106 is rotatably supported in bearings 107 and 108 (Fig. 5) in the apron 95. A worm 109 is keyed to the shaft 106 70 75

and meshes with a worm gear 110 which is rotatably journaled in a bearing 111 (Fig. 4) within the apron 95. A clutch is interposed between the worm gear 110 and the shaft 96 to facilitate automatically disconnecting the hand wheel 102 from the shaft 96 during the automatic power traverse or reciprocation of the table 20. A sleeve 112 is slidably keyed to the shaft 96 by means of a key 113. A frusto-conically shaped clutch member 114 (Fig. 4) is formed integral with the sleeve 112 and is provided with a frusto-conically shaped clutch face 115 which mates with a correspondingly shaped mating surface formed within a projecting hub of the worm gear 110. A similarly shaped frusto-conical clutch member 116 is slidably keyed to the sleeve 112 and is provided with a frusto-conically shaped clutch surface 117 which mates with a correspondingly shaped mating surface within an extended hub portion on the opposite side of the worm gear 110.

A plurality of symmetrically arranged springs 118 (only one of which has been shown in Fig. 4) serve normally to hold the clutch member 114 out of engagement with the worm gear 110, and a similar series of symmetrically arranged springs 119 serve normally to hold the clutch member 116 in a disengaged position.

A fluid pressure mechanism is provided for actuating the clutch members, which is rendered operative when the control lever 75 is shifted to stop the automatic power reciprocation of the table 20, so that when the hand wheel is turned to manually control the traversing movement of the table 20, the rotation of the hand wheel 102 will govern the speed of movement of the table 20, as will be hereinafter described. A fluid pressure cylinder 120 is formed within the hub of the worm gear 110. When fluid under pressure is admitted through a port 121 into the cylinder 120, it causes an endwise movement of a piston which, as illustrated, is the clutch member 116, into engagement with the clutch surface 117. Fluid pressure within the cylinder 120 also moves a piston member 122 within the cylinder 120 in the opposite direction which transmits an endwise movement to a thrust bearing 123 and the sleeve 112 toward the right (Fig. 4) which serves to move the clutch member 114 into engagement with the clutch face 117 on worm gear 110, thus clutching the worm gear 110 to the shaft 96. The pitch of the worm gear 110 and the worm 109 are such that the table 20 is held stationary unless the hand wheel 102 is rotated.

A fluid pressure control valve 125 serves to control the admission to and exhaust of fluid from the clutch cylinder 120. The valve 125 is a piston type valve comprising valve pistons 126, 127 and 128. A tension spring 129 serves normally to hold the valve 125 in its left-hand end position (Fig. 4). An electric solenoid 130 serves when energized to shift the valve 125 toward the right (Fig. 4) against the tension of the spring 129. An arm 131 depending from the valve member 125 is arranged in the path of a normally open limit switch 132. When the solenoid 130 is energized to shift the valve toward the right, the arm 131 engages and closes the limit switch 132. Fluid under pressure from the pump 52 passes through the pipe 53, the pipe 59, and through a pipe 135 which admits fluid under pressure to a valve chamber located between the valve pistons 127 and 128. In the position of the valve 125 (Fig. 4), the valve piston 127 cuts off fluid pressure from the port 121 and the cylinder

120 and fluid within the cylinder 120 may exhaust through a port 121 and a valve chamber located between the valve pistons 126 and 127 and out through a pipe 136 into the reservoir 50. In this position of the parts, the springs 118 and 119 above described hold the clutch parts in a disengaged position, thus disconnecting the hand wheel 102 from the shaft 96, the gear 99, the rack 100, and the table 20.

When the solenoid 130 is energized, the valve 125 shifts toward the right (Fig. 4), as above described, so that the valve piston 126 covers the port at the end of the exhaust pipe 136 and the valve piston 127 uncovers the port at the end of the pipe 135 to admit fluid under pressure to the valve chamber located between the valve pistons 126 and 127 which admits fluid under pressure through the port 121 into the cylinder 120 to cause the clutch members 114 and 116 to move into operative engagement to clutch the worm gear 110 to the shaft 96.

A yieldable connection is provided between the hand wheel 102 and the bevel gear 104. The hand wheel 102 is keyed to a rotatable member 140 and the bevel gear 104 is formed integral with a rotatable member 141. The members 140 and 141 are each provided with bearings 142 and 143, respectively, which are rotatably supported on the shaft 103. The rotatable member 140 is provided with a semi-circular recess 144 and the rotatable member 141 is provided with a correspondingly shaped recess 145. A compression spring 146 is inserted within the recesses 144 and 145 and is arranged so that the hand wheel may be turned a slight distance to compress the spring 146 before the rotary motion is transmitted to rotate the bevel gear 104. In order to limit the extent of lost motion between the rotary parts 140 and 141, the rotatable member 140 is provided with a lug 147 which rides within a recess or cut-out portion 148 in the periphery of the rotatable member 141. The purpose of this lost motion yieldable connection between the hand wheel 102 and 104 will be hereinafter described.

A metal strap 150 wraps around a groove 151 formed in the periphery of the rotatable member 140 and is frictionally held in engagement therewith by a spring 151 (Fig. 3). The strap 150 is provided with two downwardly extending arms 152 and 153, respectively, which are arranged in the path of the actuating plungers 154 and 155 of a pair of normally open limit switches 156 and 157, respectively. These switches 156 and 157 are electrically connected to control the position of a control valve 160 to be hereinafter described. The limit switch 156 is connected so that when it is closed, it energizes a solenoid 161 which serves to shift the control valve 160 toward the left (Fig. 2). Similarly, the normally open limit switch 157 is electrically connected when closed to energize a solenoid 162 to shift the control valve 160 toward the right (Fig. 2).

The control valve 160 is provided to control the admission of fluid under pressure to the cylinder chamber 35 when the table 20 is traversed under manual control. This valve is preferably a piston type valve comprising a valve stem 163 which has formed integrally therewith a plurality of valve pistons 164, 165, 166 and 167. A pair of opposed balanced springs 168 and 169 serve normally to hold the valve 160 in a central or neutral position.

It is desirable to provide a slightly reduced

- 5 fluid pressure for traversing the table 20 when under manual control. This is preferably accomplished by a pair of adjustable relief valves 170 and 171 which are connected with the pipe 53. The relief valve 170 is set to allow the pressure to build up to the required pressure for traversing the table under power during automatic reciprocation of the table 20 and also for maintaining the clutch engaged during manual

10 10 traverse, and the relief valve 171 is set for a slight reduced or lower pressure so that the pressure for moving the table when under manual control may be adjusted as desired without disturbing the normal table operating pressure.

15 15 When the lever 75 and the stop valve 55 are shifted to stop the fluid pressure reciprocation of the table 20, the pressure from the pump 52 builds up within the system and the excess fluid pressure passes through a pipe 172 to the control valve 160. The relief valve 171 is set for the reduced or low pressure desired for use in the manual traversing of the table 20. If the pressure within the pipe 172 is above the pressure for which the valve 171 is set, the excess fluid under pressure passes through the relief valve 171 and out through a pipe 173 which returns the excess

20 25

The reduced or low pressure fluid passing through the pipe 172 enters a valve chamber 30 formed between the valve pistons 165 and 166 of the valve 160 (Fig. 2). The valve 160 is connected by a pipe 175 with a left-hand cylinder chamber 176 in the cylinder 35. The valve 160 is also connected by a pipe 177 with a cylinder chamber 178 35 formed at the right-hand end of the cylinder 35.

When the solenoid 161 is energized to shift the valve stem 163 toward the left (Fig. 2), fluid under pressure passing through the pipe 172 passes out through the pipe 175 into the cylinder chamber 176 to effect a pressure tending to move the piston 36 and table 20 toward the left. In this position of the valve, fluid within the cylinder chamber 178 exhausts through the pipe 177, a valve chamber located between the valve 40 pistons 166 and 167, and out through an exhaust pipe 179, to return or exhaust fluid contained therein to the reservoir 50. Similarly, if the solenoid 162 is energized to shift the valve stem 163 toward the right (Fig. 2), fluid under pressure 45 passing through the pipe 172 to the valve 160 is admitted through the pipe 177 into the cylinder chamber 178, tending to move the piston 36 and table 20 toward the right (Fig. 2).

55 The fluid pressure admitted to the cylinder chambers 176 and 178 of the cylinder 35 when the valve 160 is operative to traverse the table is sufficient to move the table longitudinally under its given load at the desired speed. The table 20 cannot move longitudinally due to the fact that 60 before the valve 160 can be shifted to admit fluid into either table cylinder, fluid under pressure has been admitted into the cylinder chamber 120 to lock the clutch members 114 and 116 so that the worm gear 110 is clutched to the shaft 96.

65 The various mechanisms of the machine, as illustrated in the drawings, are in condition for an automatic table controlled reciprocation of the table 20. When it is desired to stop the automatic reciprocation of the table 20 and to provide a manual controlled traversing movement thereof, the control lever 75 is moved in a clockwise direction (Fig. 2) to cut off the high pressure fluid from the control valve 40 and also to cut off the exhaust of fluid therefrom.

75 The operation of this mechanism will be read-

ily apparent from the foregoing disclosure. The automatic reciprocation of the table 20 is readily apparent from the foregoing disclosure and inasmuch as this mechanism is substantially the same as that shown in the above-mentioned prior patent to Wood, the operation of this mechanism is omitted herein. 5

Assuming all of the valves and parts to have been previously adjusted and the relief valves 170 and 171 to have been adjusted to provide the desired operating pressures in the automatic and manually controlled traverse mechanisms, the lever 75 is moved in a clockwise direction to shift the valve stem 56 toward the right (Fig. 2) which serves to cut off high pressure fluid from the table cylinder 35 and also exhaust of fluid therefrom. 15

When the stop and start lever 15 is moved in a clockwise direction (Fig. 2) to stop the automatic reciprocation of the table, it engages and closes a normally open limit switch 180 which serves to energize the solenoid 130. Energizing of the solenoid 130 actuates or moves the valve 125 toward the right (Fig. 2) to admit fluid under pressure to the cylinder 120 to move the clutch members 114 and 116 into clutched engagement with the worm gear 110. When the valve 125 moves toward the right, the arm 131 engages and closes the normally open limit switch 132 to render the manual table control mechanism operative. In this position of the parts, when the manually operable table traverse wheel 102 is rotated in a clockwise direction (Figs. 1 and 3) to traverse the table 20 toward the right, the lost motion between the lug 147 and the cut-out portion 148 is taken up and the strap 150 shifts the extension 152 into engagement with the plunger 154 to close the limit switch 156 which serves to energize the solenoid 161. Energizing of the solenoid 161 shifts the valve stem 163 of the valve 160 toward the left (Fig. 2) so that fluid under pressure passing through the pipe 172 is admitted through the pipe 175 into cylinder chamber 176 to move the piston 36 and table 20 toward the right. The fluid pressure admitted to the cylinder 176 traverses the table 20 at a speed governed by the speed of rotation of the hand wheel 102 and the gear 99. The lost motion device including the spring 146 which is located between the hand wheel 102 and 104 allows a yieldable connection therebetween and facilitates closing of the electric circuit to shift the valve 160 before the gear 99 is rotated.

During the admission of fluid pressure to the cylinder chamber 176, when the table 20 and piston 36 move longitudinally, as permitted by rotation of the gear 99, fluid within the chamber 178 exhausts through the pipe 177 and out through the pipe 179 into the reservoir 50. Similarly, when the hand wheel 102 is rotated in a counterclockwise direction, the strap 150 also moves in this direction to shift its extension 153 into engagement with the plunger 155 to close the normally open limit switch 157. This movement serves to energize the solenoid 162 to shift the valve stem 163 toward the right (Fig. 2) which serves to admit fluid under pressure passing through the pipe 172 into the pipe 177 which admits fluid under pressure to the cylinder chamber 178 to exert a pressure tending to move the piston 36 and table 20 toward the left (Fig. 2). This movement of the table toward the left, as previously explained, is permitted only by the rotation of the hand wheel 102 and gear 99, the speed of which govern the traversing movement of the table 20.

During the initial rotation of the hand wheel 102 in either direction, the spring 146 is slightly compressed until either the limit switch 156 or the limit switch 157 is actuated to shift the control valve 160, whereupon continued rotation of the hand wheel serves to govern the speed of traversing movement of the table 20. When the operator stops the rotation of the hand wheel 102, the released compression of the spring 146 again shifts the hand wheel so that the strap 150 together with its extensions 152 and 153 assume the position illustrated in Figs. 2 and 3 so that whichever limit switch 156 or 157 is closed, it again opens to deenergize either the solenoid 162 or the solenoid 161, thus releasing the compression of the springs 168 and 169 which centralize the valve 160 in a neutral or central position, cutting off fluid pressure from both ends of the table cylinder 35. It will thus be seen that the speed of the manual traverse of the table is governed by the speed of rotation of the hand wheel 102 and the direction of movement of the table is governed by the direction of rotation of the hand wheel 102.

It will thus be seen that there has been provided by this invention apparatus in which the various objects hereinabove set forth together with many thoroughly practical advantages are successfully achieved. As many possible embodiments may be made of the above invention and as many changes might be made in the embodiment above set forth, it is to be understood that all matter hereinabove set forth or shown in the accompanying drawings is to be interpreted as illustrative and not in a limiting sense.

I claim:

1. In a grinding machine having a base, a longitudinally traversable table and a piston and cylinder therefor, a control valve to admit fluid under pressure to either end of said cylinder, a rack bar depending from said table, a manually operable hand wheel, gearing which is substantially irreversible interposed between the hand wheel and rack, a clutch to connect or disconnect said gearing with said hand wheel, and means controlled by rotation of the hand wheel for actuating said valve to admit fluid under pressure to said table cylinder whereby a hydraulically-actuated, manually-permitted traversing movement of the table is obtained in which the direction and speed of rotation of the hand wheel governs the direction and traversing speed of the table.
2. In a grinding machine having a longitudinally traversable table and a piston and cylinder therefor, a control valve to admit fluid under pressure to either end of said cylinder, a rack bar depending from said table and a hand traverse apron therefor including a manually operable rotatable hand wheel, a worm and worm gear operatively connected therewith, a rotatable shaft having a gear meshing with said table rack, a clutch to connect or disconnect said worm gear with said shaft, said gearing being arranged to facilitate transmission of a rotary movement from the hand wheel to the table rack longitudinally but arranged to resist power movement of said table, and means controlled by rotation of said hand wheel for actuating said valve to admit fluid under pressure to said table cylinder, whereby a hydraulically-actuated, manually-permitted traversing movement of the table is obtained in which the direction and speed of rotation of said hand wheel governs the direction and the traversing speed of the table.

3. In a grinding machine having a longitudinally traversable table, a fluid motor to reciprocate said table in either direction, a table actuated reversing valve to admit fluid under pressure to either side of said motor continuously to reciprocate said table, a stop and start valve to render said reversing valve inoperative, a second reversing valve to admit fluid under pressure to either side of said motor, a manually operable hand traverse wheel, operative connections between said hand wheel and said second reversing valve to shift said second reversing valve in either direction depending upon the direction of rotation of said wheel, a rotatable shaft and gearing operatively connected to said table, a fluid operated clutch to connect said wheel and shaft, and means including a control valve to control the admission of fluid under pressure to actuate said clutch.

4. In a grinding machine having a longitudinally traversable table, a fluid motor to reciprocate said table in either direction, a table actuated reversing valve to admit fluid under pressure to either side of said motor continuously to reciprocate said table, a stop and start valve to render said reversing valve inoperative, a second reversing valve to admit fluid under pressure to either side of said motor, a manually operable hand traverse wheel, operative connections between said hand wheel and said second reversing valve to shift said second reversing valve in either direction depending upon the direction of rotation of said wheel, a rotatable shaft and gearing operatively connected to said table, a fluid operated clutch to connect said wheel and shaft, means including a control valve to control the admission of fluid under pressure to actuate said clutch, and means actuated automatically by and in timed relation with said stop and start valve to actuate said control valve so as to engage said clutch.

5. In a grinding machine having a longitudinally traversable table, a fluid motor to reciprocate said table in either direction, a table actuated reversing valve to admit fluid under pressure to either side of said motor continuously to reciprocate said table, a stop and start valve to render said reversing valve inoperative, a second reversing valve to admit fluid under pressure to either side of said motor, a manually operable hand traverse wheel, operative connections between said hand wheel and said second reversing valve to shift said second reversing valve in either direction depending upon the direction of rotation of said wheel, a rotatable shaft and gearing operatively connected to said table, a fluid operated clutch to connect said wheel and shaft, electrically operated means to control said clutch, and an electrical control device including a switch actuated by and in timed relation with said stop and start valve to engage said clutch to render the traverse wheel operative when the latter valve is closed to stop the reciprocation of the table.

6. In a grinding machine having a longitudinally traversable table having a rock bar, a fluid motor to reciprocate said table in either direction, a table actuated reversing valve continuously to reciprocate said table, a stop and start valve to render said reversing valve inoperative, a second reversing valve to admit fluid to either side of said motor, a manually operable hand traverse wheel, operative connections between said hand wheel and the second reversing valve whereby the valve is shifted by and in timed

relation with the rotation of said hand wheel, a rotatable shaft and gearing operatively connected with a table rack bar, a fluid operated clutch to connect said wheel and shaft, a valve to control the admission of fluid to actuate said clutch, electrically operated means including a solenoid to actuate said valve, and an electrical control device including a switch actuated by and in timed relation with said stop and start valve to 10 actuate said clutch valve and engage said clutch to render the traverse wheel operative when the stop and start valve is closed to stop reciprocation of the table.

7. In a grinding machine having a longitudinally reciprocable table, a fluid motor to reciprocate said table, a table actuated reversing valve automatically and continuously to reciprocate said table, a stop and start valve to render said reversing valve inoperative or operative, a second reversing valve which is independent of the 15

first to admit fluid to either side of said motor, a manually operable hand traverse wheel, operative driving connections between said hand wheel and table, electrical solenoids to shift said second reversing valve in either direction, an electrical control device actuated by rotation of said wheel to energize one or the other of said solenoids depending upon the direction of rotation of the hand wheel to admit fluid under pressure to either side of said motor, said driving connections being arranged so that the rotative speed of said hand wheel governs the traversing speed of said table, and an electrical control switch actuated by and in timed relation with said stop and start valve to render said manually operable traverse mechanism operative only when said table actuated reversing valve is rendered inoperative. 10
